UNITED STATES PATENT OFFICE.

RUSSELL S. CARTER, OF HEWLETT, NEW YORK.

SHOCK-ABSORBER.

1,318,052.

Specification of Letters Patent.

Patented Oct. 7, 1919.

Application filed July 17, 1914, Serial No. 851,448. Renewed May 21, 1918. Serial No. 235,397.

To all whom it may concern:

Be it known that I, RUSSELL S. CARTER, a citizen of the United States, residing at Hewlett, in the county of Nassau and State 5 of New York, have invented the following-described Improvements in Shock-Abso-
sorbers.

The improvements relate more particularly to shock absorbers of the kind in which 10 the shock pressures are absorbed or stored by the resistance to movement of an oscillatory piston member working in a confined fluid resistance medium, and comprise several features independently and in combination, adapting such absorbers for more convenient and economic manufacture, for greater convenience in application to the parts between which the shock is to be absorbed, for producing a difference between 15 the impact and recoil resistances, for adjusting the absorbing action and for improving the general efficiency and utility of such absorbers. More especially these improvements are related to the shock absorber for 20 automobiles shown in my co-pending Patent No. 1,171,169, dated February 8, 1916; and wherein the shock energy is transmitted to the resistance medium through a spring-
yielding member that reacts against and 25 modifies the action of the vehicle springs. Reference may be had to such application for such unclaimed matter appearing herein 30 that is common to both devices.

In the accompanying drawings, which 35 illustrate the principle of the present improvements and the best mode in which I have contemplated applying that principle,

Figure 1 is a vertical section of the improved shock absorber;

Fig. 2, a central section of Fig. 1, with parts in elevation;

Fig. 3, a side elevation detail of the mode of attachment of the absorber;

Fig. 4, a detail elevation of the blade and hub;

Fig. 5, a detail in a larger scale, of one of the adjustment parts;

Fig. 6, a perspective detail of the wall plate;

Fig. 7, a section of a modified form; and

Figs. 8 and 9, are sections of a further modification.

In general, the absorber is comprised of a casing of sector shape adapted to contain

and confine the liquid resistance medium, 55 and a blade member dividing the liquid in two portions and adapted to oscillate relatively through the liquid so as to cause it to flow from one side to the other thereof, and also suitable connecting means whereby the 60 casing on the one hand and the blade member on the other, are attached respectively to the parts between which the shock is to be controlled. The casing comprises a body wall 1, of uniform width, and cast or formed 65 of sheet metal, as desired. In the present case, it is made of a short section of rolled seamless tubing of proper diameter pressed into the general sector shape shown, and is hence not only made of sheet metal but is 70 also without seam or joint. The side wall 2 of the casing is flat, of sheet metal if desired, and formed with a chine groove adapted to receive one edge of the body wall 1, while the opposite side wall 3 is similarly 75 formed and grooved to receive the opposite edge of said wall, both side walls being provided with external bolt holes, by means of which they are clamped firmly against the body. With the aid of red lead the joints 80 thus formed may be made leak-proof without special machining of the meeting parts.

The side wall 3, in the present case, is extended beyond the arc-shaped part of the body wall in the form of a taper-curved 85 arm 4, by means of which the casing member of the device can be connected to one of the parts between which shock is to be absorbed,—for example, to a clamp 5 on the axle or spring clip of a motor vehicle. 90

The blade member 6 is formed of laminated springs bolted in a slot in the hub 7, which is journaled at the axial center of the sector-shaped casing. The width of the blade substantially equals that of the casing, 95 fitting it snugly, and the portion of the hub beyond the ends of the blade slot therein are received in circular bosses struck up from the cover plates or side walls for the purpose. One end of the hub, of reduced diameter, projects through the boss in the side plate 3, and is squared and also threaded to receive the parts which connect the blade member with the other part between which shock is to be controlled. The shouldered end of the hub within the casing is adapted 100 to seat upon the adjacent margin of the hole through the boss and is grooved to receive

a packing ring 8. A dished spring 9 housed in a recess in the opposite end of the hub serves to keep the shouldered end pressed firmly against the packing ring and the pressure of the liquid acting on the end of the hub supplements the action of the spring. The hub fits the hub part of the casing concentrically and without leaving any appreciable passage for the flow of liquid around it, the blade-holding bolt being appropriately countersunk and clamping the blade through an interposed plate 7^a, as indicated.

The connection means comprise a stub arm 10 (Fig. 5) which fits on the squared end of the hub and is provided with a circular boss 11, to form an adjustment bearing for the main connection arm 12. The latter is provided with a circular hole to fit the boss and a nut and washer 13 hold both arms together and upon the hub. The stub arm 10, by being fitted to the squared end of the hub holds a permanent angular relation to the blade 6, and the main arm 12 being pivotally mounted on the stub, can be set at any desired angle with reference thereto and to the blade. For this purpose, the stub arm is slotted at its free end and a bolt 14 is provided to clamp it firmly to the main arm in different positions of adjustment, and for the same purpose the opposite engaging faces of the two arms are serrated as indicated. When the free end of the arm 12, is connected to the chassis frame 15 of an automobile, for instance, with the casing arm 4 connected to the spring clamp thereof, loosening of the nut 13 and the bolt 14 will then allow the stub arm, hub and blade to be turned in the casing until the blade assumes some predetermined position therein with reference to the top and bottom of the liquid chamber, whereupon, by tightening the parts, such adjustment may be made permanent. The space between which the shock absorber is to be connected varies widely in different makes and weights of automobiles and it is desirable that the blade should hold a mid-position when the said space has its normal magnitude; otherwise, the blade might strike the casing on an extreme throw in one direction. By virtue of the adjustment just described, the blade 6 can be brought to its desired mid-position irrespective of the normal separation of the vehicle frame and axle and the absorber is thereby readily accommodated to various types of vehicle. It will be understood that such blade adjustment as is ordinarily required, though most important to be effected, is in any event not large in amount, and for this reason the serrations of the stub and main arms are fine and close together so as to permit the angle to be changed through small degrees of arc. It should be noted in passing that the parts constituting the described adjustment, are applicable to any

shock absorber of the oscillatory liquid resistance type, irrespective of the particular construction of the shock-resisting elements.

The liquid resistance medium, which may be castor oil or any other mobile medium, is introduced through the filling hole 1^a into the interior chamber of the casing, where it occupies the space on both sides of the spring-yielding blade therein. By virtue of the connections above described this blade alternately transmits the shock pressure to the liquid on one side or the other, causing it to flex the blade and flow around and through the passage between the free flexing end thereof and the end wall of the chamber. In its straight or unflexed condition the blade may substantially meet the end wall of the casing, so as to isolate the two compartments of the chamber, but when flexed by the inertia and pressure of the liquid, the area of the passage around its end varies in proportion to the extent of flexure, *i. e.*, to the suddenness of the shock, as described in the patent referred to. The end wall of the liquid chamber may be substantially concentric to the axis of the blade-hub, but according to one part of the present invention the said end wall is subject to adjustment with respect to its curvature and also with respect to its distance from the blade, so that different resistance effects can be produced. In such case, the effective end wall of the liquid chamber is a supplemental part separate from but adjacent to the arcuate end wall of the main casing, and as shown in Figs. 1, 2 and 6, this supplemental wall is formed by a spring plate 17, having a slotted boss 18 for connection to the grooved end of the screw 16 and by which it is held with its ends resting or pressing at the ends of the curved part of the casing wall 1, and its center part bowed outwardly under tension by virtue of its connection with the screw. The said plate it will be observed presents a large area exposed to the pressure of the liquid, substantially as large as the spring-blade itself when the latter is at the end of its stroke.

In the form of Fig. 1, one end of the adjustable chamber wall is held in a groove 19, and the other end rests by its spring pressure against the casing wall, or against a rib or ribs 2^a which form a seat for it. The wall occupies the full width of the casing and a hole 20 is formed in it at a point slightly below the center. As thus arranged the downward movement of the blade 6 not only forces the oil around its free end, as above stated, but also forces it through the hole 20 and into the space between the supplemental wall and the casing wall, from which it escapes to the other compartment by lifting the upper end of the former against such pressure as may be imposed by the flexure of the wall by the

screw 16. After the blade overrides the hole 20, the liquid yet remaining can escape only past the end of the blade and on the return stroke all of the displaced liquid 5 must pass—in the opposite direction—past the end of the flexed blade because the pressure closes the upper end of the wall 17 against its seat, as will be evident.

The passage between the supplemental 10 wall 17 and the casing wall thus forms a by-pass for the liquid which is spring-loaded to liquid flow in one direction and permits no flow at all in the opposite direction, thereby producing a low resistance to 15 the initial part of the down-stroke of the blade, a greater resistance to the remainder of that stroke and to all of the up-stroke. In the present case the down-stroke conforms to the compression of the vehicle 20 springs and the approach of the axle and frame of the vehicle, and it may be termed the impact stroke of the absorber. The up-stroke resulting from the relative separation of the axle and frame may be similarly 25 termed the recoil stroke of the absorber, but the arrangement of the resistances as just described may be reversed if desired, and according to the character of the vehicle springs.

30 It will be observed that adjustment of the screw 16 will vary the area of the flow passage around the piston member or spring blade 6, in greater degree at its point of connection with the elastic wall 17 than elsewhere, and the said screw is located at a mid-point in the stroke of the blade, so as to be capable of providing the widest passage at about that point. This gives a mid-region in which the vibration of the blade 40 is relatively unrestrained and is desirable in order to relieve the vehicle springs of the retarding influence of the shock absorber during their minor vibrations. According to the structure of the wall 17 and the disposition of its seating means 2^a, this adjustable region of relatively unrestrained vibration may be made of large or small extent, as preferred, so that a desirable portion at the end of each stroke will be left to provide 45 the principal resistance.

In the modified form of Fig. 7, the movable chamber wall 21, fits the casing at both ends and is imperforate, save for a negligible opening at the point of its attachment 55 with the screw 16. Except as modified by other agencies, the liquid resistance in this form is the same in both impact and recoil, no by-pass being present. Variation of curvature of the wall will therefore control 60 merely the flow passage around the flexing end of the blade, providing more or less resistance to the minor vibrations of the vehicle springs. This form of the apparatus having the auxiliary wall member, with- 65 out limitation to the by-pass in rear thereof,

forms the subject of another application, Serial No. 76,103, filed February 4, 1916.

In the form of Figs. 8 and 9, the casing is shown as a casting with an offset by-pass chamber at its arcuate end of less width 70 than the width of the casing and of less length than the height of the chamber. An elastic valve plate 22 covering such chamber, is held to the casing by the edges of its wider portion which fit in two slideway 75 grooves 23, being capable of adjustment therein so as to cover more or less of the chamber. A screw 24, entering the end of the chamber and connected with an out-turned ear 25 at the end of the elastic by- 80 pass wall, serves to advance or withdraw the same over the chamber as circumstances may require. In the down stroke, the liquid is forced past the screw 24 into and through the by-pass chamber, lifting the end of the 85 elastic wall 22. After passing the entrance to the by-pass chamber, the blade 6 encounters increased resistance, as in the case of Fig. 1, and during its return stroke the resistance is still increased, since the pressure closes the wall 22 against its seat. However, such return resistance may be varied by operating the screw 24 to withdraw the blade from the end of the chamber, leaving 90 a restricted reverse flow for the liquid, but 95 the full liquid resistance will be effective, in all adjustments, toward the end of the stroke in one direction.

As a further means of increasing the difference in resistance of the absorber in the 100 strokes in opposite directions, the laminations, of the blade 6 are arranged so as to permit the longest leaf 30, which is relatively thin, to flex more readily upward than downward. Thus, on the upper side 105 the successive blade leaves 31 are but three in number, while on the opposite side, the leaves 32 are four in number, and generally longer than the others. All the leaves, except 30 are fishtailed, and the next adjacent 110 leaves 31 and 32 on opposite sides of the thin leaf 30 are double-fishtailed so as to provide central fingers 31^a and 32^a, respectively, as additional backing support. The fishtailing of the several leaves not only provides a uniform flexing curve of the blade as a whole, but in the present case provides relatively wide edges to the blade in proportion to its elasticity and a correspondingly wide crevice between it and the cover- 115 plates 2 and 3. This wide crevice tends to prevent the liquid from flowing around the edges of the blade and compels it to pass from one side to the other through the passage space provided for it.

As a further means of stiffening one stroke and modifying the spring resistance of the other, the slot in the hub 7 is cut away on the upper side so that during the impact 120 the blade may bend on a longer radius but 125 130

on the recoil will bend over the edge 38 of the washer-plate 7^a representing the center of a shorter radius, the spring blade being thus made virtually longer and more yielding on one stroke than on the other. The blade may normally sweep nearly the whole arcuate distance between top and bottom walls of the casing, but as precaution against injury from contact between blade and casing on an extreme vibration, the convergence of the top and bottom walls is made at such an angle as will cause the tip or more slender part of the blade to strike the wall first, as diagrammatically indicated by dotted lines in Fig. 1, and thus cushion the blow by the resilience of the blade itself.

As will be observed in Fig. 3, the connection arm 12 is provided with a longitudinal slot 12^a extending the greater part of the length thereof and dividing the said arm into two relatively slender limbs. This divided formation provides a greater degree of lateral flexibility in the said arm than would otherwise be present and greater than is present in the other connection arm 4, thus permitting it to flex laterally and twist when accommodating lateral displacement of the chassis frame without straining the various connections, but it is otherwise adequately rigid in the vertical direction.

It will be evident that various changes may be made in the size, proportion and general arrangement of the parts above described, and also that various other forms of elastic chamber walls may be substituted for the specific wall above described, and that various other modifications may be made within the scope of the following claims and without departing from the principle of the invention.

I claim:

1. The combination with the springs of a vehicle of a shock absorber, a liquid confined therein and means for imparting the shock pressure to such liquid to cause it to flow from one side to the other of the casing, comprising a laminated spring blade member, the leaves thereof being arranged to permit the member to bend more readily in one direction than in the other.
2. The combination with the springs of a vehicle of a casing, a resistance liquid therein, and means for imparting the shock pressure to the liquid comprising an oscillating spring blade, the mounting for said blade providing supporting abutments therefor disposed on opposite sides thereof and at different distances from the free end of the blade.
3. In a shock absorber, the combination of a casing containing a resistance liquid, a laminated spring blade mounted to oscillate in the liquid and comprising a thin leaf and relatively thick supporting leaves.
4. A shock absorber comprising a casing

having parallel side walls, a laminated spring blade filling the width between such walls and composed of a main leaf and fish-tailed side leaves of graded length.

5. In a shock absorber, the combination of a liquid chamber, a hub-mounted piston member adapted to cause the liquid to flow from one part of the chamber to another, and an elastic wall adjacent the free end of the piston member, forming a by-pass through which the flow of liquid flexes said wall.

6. In a shock-absorber, the combination of an oscillating piston, a chamber therefor containing liquid which receives the shock-pressure from the piston, the wall of such chamber adjacent the swinging end of the piston being elastic, and forming a by-pass liquid passage behind it and means for varying the resistance opposed by the wall to the passage of liquid moving through the by-pass.

7. A vehicle shock-absorber comprising a main casing, a hub-supported oscillating blade therein, a supplemental wall in the casing adjacent the free end of the blade, said wall having an opening and forming a by-pass passage between it and the wall of the casing.

8. A vehicle shock absorber comprising a sector-shaped casing, a hub-supported spring-yielding blade therein, an elastic wall in the casing opposed to the swinging edge of the blade and forming a by-pass between itself and the casing wall, and means in the latter wall for controlling the flexure of the said elastic wall.

9. A vehicle shock-absorber comprising a liquid-containing casing, a hub-supported spring-yielding blade adapted to impart shock pressures to the liquid, a by-pass passage having an entrance which is overridden by the blade in its stroke in one direction and a means for preventing flow through the by-pass on the return stroke.

10. A vehicle shock absorber comprising a chamber containing liquid, a spring-yielding blade adapted to impart shock pressures to the liquid to cause it to flow around the flexing end thereof, a spring-yielding member forming a by-pass passage through which the liquid may flow in one direction, said member being arranged to resist such flow.

11. A vehicle shock absorber comprising a liquid-confining casing, a hub-supported spring-yielding blade therein by means of which the liquid is caused to flow around the flexing end of such blade, a spring-loaded by-pass for such liquid operative during part of one stroke, and means for preventing by-passage of liquid through it during the return stroke.

12. A vehicle shock absorber comprising a liquid-confining casing, a spring blade

therein by means of which the liquid is caused to flow around the flexing end of such blade, a spring-loaded by-pass for the liquid and means exterior of the casing for changing the said spring-load.

13. A shock-absorber comprising a piston mounted on a hub and oscillating in a chamber containing liquid, said chamber having an elastic wall coextensive with the normal stroke of the piston, and forming a by-pass passage in rear of said wall controlled thereby.

14. A shock absorber comprising a generally sector-shaped liquid containing chamber, a hub-mounted piston adapted to oscillate therein and having yielding abutment contact with said chamber by a point near its free end.

15. In a shock absorber, the combination with a liquid-containing casing of an oscillatory piston therein, a hub for such piston journaled in the casing and projecting to the exterior thereof, a stub-arm non-rotatably fixed on the hub and provided with a circular boss or bearing, and an operating arm for said piston journaled on the said bearing and adjustably connectible to the stub-arm in different angular relations.

16. A shock absorber comprising a casing

having sheet-metal side walls, an attachment arm extended from one of said side walls, and a body of liquid confined in said casing, in combination with a hub journaled in said casing, a piston on the hub within the casing and an attachment arm secured to said hub and formed of two vertically superposed, thin limbs adapting said arm to twist or flex laterally.

17. A shock absorber comprising a liquid-containing chamber, and a hub-mounted spring-yielding piston therein, the terminal wall surface of said chamber being disposed in position adapting it for contact with the free end of said piston on extreme strokes.

18. A shock absorber comprising a liquid-containing chamber, a piston member therein, an elastic chamber wall subject to deflection by the liquid and having an area substantially equal to the area of the piston exposed to such liquid, and a by-pass passage controlled by said elastic wall.

In testimony whereof I have signed this specification in the presence of two witnesses.
